US0D1003332S

(12) **United States Design Patent** (10) **Patent No.:** **US D1,003,332 S**
(45) **Date of Patent:** **** Oct. 31, 2023**

(54) **OPTICAL DEVICE**

(71) Applicants: **SINTAI OPTICAL (SHENZHEN) CO., LTD.**, Shenzhen (CN); **ASIA OPTICAL CO., INC.**, Taichung (TW)

(72) Inventors: **Hua-Tang Liu**, Taichung (TW); **Han Lu**, Taichung (TW); **Chun-Guang Zhang**, Taichung (TW)

(73) Assignees: **SINTAI OPTICAL (SHENZHEN) CO., LTD.**, Shenzhen (CN); **ASIA OPTICAL CO., INC.**, Taichung (TW)

(**) Term: **15 Years**

(21) Appl. No.: **29/799,170**

(22) Filed: **Jul. 13, 2021**

(30) **Foreign Application Priority Data**

Jan. 19, 2021 (TW) 110300282

(51) **LOC (14) Cl.** **16-06**

(52) **U.S. Cl.**

USPC **D22/109**; D16/132

(57) **CLAIM**

The ornamental design for an optical device, as shown and described.

DESCRIPTION

FIG. 1 is a front, left perspective view of an optical device, showing our new design;

FIG. 2 is a rear, right perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the optical device that form no part of the claimed design.

1 Claim, 8 Drawing Sheets
